AIR CONDITIONING SYSTEM

Robert B. P. Crawford, Miami, Fla.

Application February 6, 1939, Serial No. 254,839

14 Claims. (Cl. 62—6)

This invention relates in general to air conditioning and is more particularly concerned with air conditioning systems of the type utilizing a refrigeration system for heating and cooling.

An object of this invention is the provision of a heating and cooling system utilizing a refrigeration system having an evaporator and condenser which are selectively connected to a space heat exchange means to thereby provide for heating or cooling the space without altering the operation of the refrigeration system.

Another object is the provision of a system of this type which utilizes first and second space heat exchangers which are alternately connected to the evaporator and condenser of the refrigeration system.

A further object is the provision of a system of this general type which utilizes a storage tank for storing conditioned medium and in which the temperature of the stored medium is automatically controlled. Still another object is the provision of a timing arrangement for stopping the refrigeration system during peak load periods and for varying the temperature of the stored medium prior to such periods to provide for carrying the system through such periods.

Other objects will appear from the following description and the appended claims.

For a full disclosure of this invention, reference is made to the following detailed description and to the accompanying drawings, in which

Figure 1 illustrates diagrammatically an air conditioning system embodying the principles of this invention, and

Figure 2 is a wiring diagram of the control system of Figure 1.

Referring to the drawings, reference character 1 indicates a conditioning chamber having an inlet 2 for fresh air. The discharge end of this conditioning chamber is connected to a fan 3 which in turn is connected by a discharge duct 4 to the conditioned space 5. This conditioning chamber contains a first heat exchanger 6 which acts as a precooler for the air in summer and as a preheater for the air in winter. Also located in chamber 1 is a second heat exchanger 7 which acts as a cooling coil in summer and as a heating coil in winter. While chamber 1 is illustrated as receiving fresh air only, this chamber may be arranged to receive a mixture of fresh air and air recirculated from the space 5, if so desired.

The cooling and heating system includes a mechanical refrigeration system having a compressor 8 which is driven by an electric motor 9 controlled by a three speed starting box 10. The

outlet of the compressor 8 is connected by a discharge line 11 to the refrigerant inlet of a condenser 12 which is diagrammatically illustrated as comprising a casing housing a cooling coil 13. The refrigerant outlet of the condenser 12 is connected by a liquid line 14 to a solenoid valve 15 which is in turn connected by pipe 16 to an evaporator 17. This evaporator 17 is provided with a coil 18. The top of the evaporator 17 is connected to a suction line 19 having a trap 20 interposed therein for removing any liquid refrigerant which may be withdrawn from the evaporator. The trap 20 is provided with a drip conduit 22 which is connected to the inlet pipe 16. The solenoid valve 15 is controlled by means of a float switch 23 which is responsive to the level of the liquid refrigerant in the evaporator 17. This float switch opens and closes the valve 15 in a manner to maintain a constant liquid refrigerant level in the evaporator and thus causes the evaporator 17 to be flooded. As well understood in the art, the condenser 12 acts to remove heat from the compressed refrigerant thereby liquefying it, and this liquid refrigerant evaporates within the evaporator 17 for causing the coil 18 to be chilled.

Reference character 25 indicates a circulating pump which is driven by an electric motor 26. The inlet of this pump is connected to a pipe 27 which extends into a well 28. The discharge of pump 25 is connected to a pipe 29 which leads to the inlet of the coil 6 located within the conditioning chamber 1. The water flows through this coil in counterflow relation with the air flow through the conditioning chamber. The outlet of coil 6 is connected to a pipe 30 which in turn is connected to valves 31 and 32. The outlet of valve 31 is connected to a pipe 33 leading to the inlet of coil 18 within the evaporator 17, and the outlet of this coil is connected by a pipe 34 which is in turn connected to valves 35 and 36. The outlet of valve 35 is connected to pipe 37 which leads into a sump 38 which is connected to the well 28 by a subterranean ditch 39 located below the prevailing water table. The valve 32 is connected to a pipe 40 which leads to the inlet of the coil 13 in condenser 12. The outlet of this coil is connected by a pipe 41 to a modulating valve 42 which is in turn connected by pipe 43 to the inlet of a three-way valve 44. One outlet of this three-way valve is connected by pipe 45 to a storage tank 46, this tank in turn being connected by pipe 47 to the pipe 48 which extends between valve 36 and the inlet of a pump 49. This pump is driven by a motor 50 having

a starter 51. The outlet of this pump is connected by a pipe 52 to the inlet of coil 7 in conditioning chamber 1. The water or other heat exchange medium passes through this coil 7 in counterflow relationship to the air being conditioned, and leaves this coil through a pipe 53 which is connected by pipes 54 and 55 to valves 56 and 57, respectively. The second outlet of the three-way valve 44 is connected by a pipe 58 which leads to the sump 38. The pipe 40 which leads to the inlet of coil 13 in condenser 12 is connected to a city water service pipe 59, the flow through this pipe being controlled by means of a valve 60 which is controlled by a proportioning motor 61.

The valves 31, 32, 35, 36, 56, and 57 may be solenoid valves which are adapted to close when deenergized and to open when energized. In a manner which will be explained hereinafter, the valves 31, 35, and 57 are energized when the system is operating on the winter cycle and these valves are marked "W". The valves 32, 36, and 56 are deenergized during the winter cycle and are energized during the summer cycle and are accordingly marked "S".

Thus during the winter cycle, the W valves are open while the S valves are closed. With the valves in these positions, the pump 25 will act to withdraw water from the well 28, which water will be higher than the temperature of the incoming air. This water will be discharged through the pipe 29 into coil 6 through which it flows in counterflow relationship with the air thereby preheating the air. This water will then flow through the pipe 30, valve 31, and pipe 33 into coil 18 of the evaporator 17, and thereby provides a source of heat for this evaporator. This water will then flow through pipe 34, valve 35, and pipe 37 into sump 38 from which it may flow through the subterranean ditch 39 back to the well 28. The water in flowing through this ditch located below the water table will absorb heat from the surrounding sub-strata and water. At the same time, water will be withdrawn from the storage tank 46 through pipes 47 and 48 by the pump 49, this pump discharging this water through the pipe 52 and into the coil 7. The water will flow from the coil 7 through pipes 53 and 55, valve 57 and pipe 40 into the coil 13 in condenser 12. The water in flowing through this coil will be heated by the compressed gaseous refrigerant, and will flow from this coil through pipe 41, valve 42, and pipe 43 to the three-way valve 44. In a manner which will be explained hereinafter, the valve 44 is caused to close off its upper outlet so that all of the heated water flows through the pipe 45 into the storage tank 46. This storage tank may have a take-off 46a for domestic hot water.

During the cooling cycle the W valves 31, 35, and 37 will be closed while the S valves 32, 36, and 56 will be open. At this time, the well water will be cooler than the air passing over coil 6 and consequently the pump 25 in forcing water from the well 28 through coil 6 causes the air to be precooled. The water flowing from the coil 6 passes through pipe 30, valve 32, and pipe 40 into the coil 13 of condenser 12 for condensing the compressed refrigerant. The heated water flowing from coil 13 passes through pipe 41, valve 42, and pipe 43 to the three-way valve 44. This water will then flow through the pipe 58 back to the sump 38 if the valve is in the position illustrated, or will flow through the pipe 45 into the

storage tank 46 if the valve 44 is positioned to permit this.

Also at this time, the pump 49 will withdraw cold water from the coil 18 of evaporator 17 through pipe 34, valve 36 and pipe 48. This cold water will pass through the pipe 52 into the coil 7 for thereby cooling the air being passed to the space. The water leaving this coil will flow through pipe 53, pipe 54, valve 56, and pipe 33 to the inlet of coil 18 in the evaporator 17.

From the description thus far, it will be apparent that during both the heating cycle and the cooling cycle the pump 25 will act to withdraw water from the well 28 and pass it through the coil 6 in the conditioning chamber 1. During the heating cycle this will act to preheat the air and during the cooling cycle this will act to pre-cool the air. Also it will be apparent that when the system is operating on the cooling cycle, the water leaving the coil 6 will be passed through the condenser 12 for thereby condensing the refrigerant and this water will then flow into the sump 38. Also at this time, the water is circulated from the coil 18 in evaporator 17 through the coil 7 in conditioning chamber 1 for thereby cooling the air and the water leaving the coil 7 is passed directly back to the inlet of coil 18. When the system is operating on the heating cycle however, the water leaving the coil 6 which then acts as a preheater will pass directly into coil 18 of evaporator 17 for thereby providing a source of heat and the cold water leaving coil 18 will pass to the sump 38. At this time, hot water is withdrawn from the storage tank 46 and passed through the coil 7 in conditioning chamber 1. This water then passes through valve 57 into the inlet of coil 13 in which it is heated, the hot water passing through the valves 42 and 32, valve 43 back into storage tank 46. Thus in summer the coil 7 receives cold water from the evaporator 17 and in winter this coil receives hot water from the condenser 12.

Referring now to the controls for the system, reference character 65 indicates a thermostat responsive to outdoor temperature, this thermostat controlling a motor 66 operating a step controller 67. This step controller 67 is connected to the W and S valves and acts to open the S valves 32, 36, and 56 when outdoor temperature rises above 75° F. and to open the W valves 31, 35, and 57 when outdoor temperature falls below 60° F. This step controller 67 also is connected to the pump motor starter 51 for stopping this pump 49 when outside temperature is between 60° F. and 75° F., while causing operation of this pump when outside temperature varies above or below this range. The compressor starter 10 is of the three-speed type and is controlled by means of a step controller 68 which is actuated by a motor 69. This motor 69 is controlled through a relay 70 which in turn is controlled by the step controller 67. This relay 70 acts to place the step control motor 69 under the control of a summer space thermostat 71 when the outside temperature is above 75° F., while placing this step control motor 69 under the control of a winter space thermostat 72 and a low limit discharge thermostat 73 when outside temperature is below this value. The step controller 67 also operates through a relay 74 in the compressor starter circuit for preventing operation of the compressor when outside temperature is between 60° F. and 75° F. The three-way valve 44 and the city water valve 60 are selectively controlled by means of a pressure controller 75 on

the hot water tank 46 through a relay 16 which is controlled by the step controller 67. This relay acts to place the controller 75 in control of the valve 61 when the system is operating on the heating cycle while placing the controller 75 in control of the three-way valve 44 when the system operates on the cooling cycle. The throttling valve 42 is controlled by a thermostat 77 which is responsive to the temperature of the water in tank 46 and also by a timer 78 which functions to vary the setting of controller 77 in a manner to increase the temperature of the water in tank 46 to a predetermined value before a peak load period for the power service approaches. This timer 78 also functions to prevent operation of the compressor during such peak load periods.

Referring now to Figure 2, the details of the control system will be described. The outside thermostat 65 is preferably of the potentiometer type and is diagrammatically illustrated as comprising a bellows 80 connected by tube 81 to a bulb 82 located in the fresh air inlet. This bellows actuates a bell-crank lever having an actuating arm 83 connected to a spring 84 and a slider 85 which cooperates with a control resistance 86 to form a control potentiometer. It will be apparent that upon rise in temperature of the fresh air the bellows 80 will expand thus causing movement of slider 85 to the right along resistance 86 against the action of spring 84, and that upon fall in temperature the bellows 80 will contract under the action of spring 84 for causing movement of the slider in the opposite direction. This instrument may be so designed and adjusted as to cause slider 85 to engage the right-hand end of resistance 86 when outdoor temperature is at or above 75° F., while engaging the left-hand end of this resistance when outdoor temperature is at or below 60° F.

The motor 66 which actuates the step controller 67 is preferably of the type shown in the Taylor Patent No. 2,028,110. This motor is connected to the thermostat 65 and is adapted to assume angular positions corresponding to the position of the slider 85 on resistance 86. This motor 66 is provided with a shaft 87 which carries the step controller cams 88, 89, and 90. These cams cooperate with suitable followers for actuating mercury switches 91, 92, and 93, respectively. When outside temperature is at or above 75° F., the shaft 87 of motor 66 assumes the extreme clockwise position shown at which the raised portions of cams 88 and 90 just engage the cam followers for tilting mercury switches 91 and 93 so as to bridge the left-hand electrodes of switch 91, and the electrodes of switch 93. At this time, the raised portion of the cam 89 engages the cam follower for mercury switch 92 and tilts this switch to open position. Upon fall in outside temperature, the slider 85 of thermostat 65 will begin to move to the left on resistance 86 which causes proportionate rotation of shaft 87 in a counter-clockwise direction. This immediately causes the raised portions of cams 88 and 90 to disengage their respective cam followers thereby tilting mercury switch 91 for bridging its right-hand electrodes and tilting mercury switch 93 to open position. When outside temperature falls to 60° F., the shaft 87 will have rotated sufficiently to cause the raised portion of cam 89 to disengage its follower for thereby tilting mercury switch 92 to closed position. It will therefore be seen that when outside temperature is at or above 75° F., the mercury switch 92 will be open, the mercury

switch 93 closed, and the left-hand electrodes of mercury switch 91 will be closed. When outside temperature is between 75° F. and 60° F., the mercury switches 92 and 93 will both be open and mercury switch 91 will be tilted for bridging its right-hand electrodes. When outside temperature is below 60° F., the mercury switch 92 will close and the right-hand electrodes of switch 91 will remain bridged.

The mercury switches 91 and 92 control the S valves 32, 36, and 56 and the W valves 31, 35, and 57. When the outside temperature is at or above 75° F., the switch 93 is closed and the switch 92 is open as described above. Due to switch 93 being closed, a circuit will be completed from the secondary 94 of step-down transformer 95, wire 96, wire 97, mercury switch 93, and wire 98 through the S valves 32, 36, and 56 and wires 99 and 100 back to secondary 94. This circuit energizes the S valves 32, 36, and 56 and thus causes these valves to open. At this time the mercury switch 92 is open and the W valves 31, 35, and 57 are deenergized and consequently are closed. When outside temperature falls below 75° F., but is above 60° F., both the S valves and W valves will be deenergized due to mercury switches 92 and 93 being open. Upon fall in outside temperature below 60° F., the mercury switch 92 will close which will complete a circuit from the transformer secondary 94, wires 96, 101, and 102, mercury switch 92, and wire 103 through W valves 31, 35, and 57 in parallel to wire 104 and wires 105, 99 and 100 to secondary 94. Therefore when outside temperature is above 75° F., the S valves 32, 36, and 56 are open and the W valves 31, 35, and 57 are closed. When outside temperature is between 75° F. and 60° F., all of the valves will be closed, and when the temperature falls below 60° F. the S valves 32, 36, and 56 will remain closed and the W valves 31, 35, and 57 will open.

Referring now to the compressor speed controls, the compressor motor 9 is of the three-speed type and is provided with the three-speed starting box 10. This three-speed starting box is provided with a common terminal connected to wire 107, a low speed terminal connected to wire 108, an intermediate speed terminal connected to wire 109, and a high speed terminal connected to wire 110. The wires 108, 109, and 110 lead directly to the step controller 68 and the wire 107 leads to the relay 74.

The relay 74 may be of any desired type and is diagrammatically illustrated as including a pull-in coil 111 which actuates a switch arm 112 through a suitable armature 113. When coil 111 is energized, the switch arm 112 is caused to engage contact 114, while when coil 111 is deenergized the switch arm 112 disengages contact 114 due to the action of gravity or springs, not shown.

The step controller 68 includes cams 115, 116, and 117 which are mounted upon the shaft 118 of motor 69 and which through suitable followers actuate mercury switches 119, 120, and 121. The cams 115, 116, and 117 are attached to the shaft 118 in staggered relationship so that upon clockwise rotation of shaft 118, the mercury switches 119, 120, and 121 are sequentially closed in the order stated. When the shaft 118 of motor 69 is in its extreme counterclockwise position, the mercury switches 119, 120 and 121 will all be open and consequently the compressor motor 9 will not operate. As shaft 118 rotates in a clockwise direction, mercury switch 119 will first close. As

suming that relay 74 is energized, a circuit will be completed from the common terminal of starter 10 through wire 107, relay 74, wires 122 and 123, mercury switch 119, and wire 108 to the low speed terminal of the starter 10 thereby causing the compressor to operate at low speed. Upon further rotation of shaft 118, the mercury switch 120 will close for thereby completing a circuit from the common terminal through this switch and wire 109 to the intermediate speed terminal for causing operation of the compressor at intermediate speed. Upon still further rotation of shaft 118, the mercury switch 121 will close for completing a circuit through wire 110 to the high speed terminal thereby causing the compressor to operate at high speed. From the foregoing, it will be apparent that the compressor speed will vary in accordance with the angular position of the shaft 118 when the relay 74 is energized. It will also be apparent that when relay 74 is de-energized, the compressor will not operate regardless of the position of shaft 118.

The motor 69 is preferably of the type shown in the Taylor Patent No. 2,028,110 and is controlled by the relay 70, the summer thermostat 71, the winter thermostat 72, and the discharge thermostat 73. The summer thermostat may be of the potentiometer type and includes a bellows 125 which actuates a bell-crank having an actuating arm 126 biased by a spring 127, and a control arm or slider 128 which cooperates with a resistance 129 to form a control potentiometer. Upon an increase in space temperature, the bellows 125 will expand against the action of spring 127 for shifting the slider 128 to the left along resistance 129, while upon decrease in temperature the bellows 125 will contract under the action of spring 127 for shifting slider 128 in the opposite direction. This instrument may be so designed and adjusted as to cause the slider 128 to engage the right-hand end of resistance 129 when space temperature is at or below 75° F., while engaging the left-hand end of this resistance when space temperature is at or above 80° F.

The winter space thermostat 72 may be exactly the same as the summer thermostat 71 and includes a slider 130 and a resistance 131. This instrument may be designed and adjusted in a manner to cause the slider 130 to engage the left-hand end of resistance 131 when the space temperature is at or above 72° F., while engaging the right-hand end of this resistance when the space temperature is at or below 70° F.

The discharge thermostat 73 may be similar to the space thermostats 71 and 72 and includes a bellows 132, a slider 133, and a resistance 134. In this case, however, the bellows 132 is connected by a capillary tube 135 to a bulb 136 located in the discharge duct 4 (Figure 1). This instrument may be designed and adjusted to cause the slider 133 to engage the left-hand end of resistance 134 when the discharge temperature is at or above 65° F., while engaging the right-hand end of this resistance when the discharge temperature falls to 62° F.

The relay 70 includes a pull-in coil 137 which actuates through a suitable armature the switch arms 138, 139, and 140 which cooperate with "in" contacts 141, 142, and 143, respectively, and also which cooperate with "out" contacts 144, 145, and 146, respectively. When coil 137 is energized, the switch arms 138, 139, and 140 engage the "in" contacts, while when coil 137 is deen-

ergized, the switch arms engage the "out" contacts.

As mentioned before, the motor 69 is preferably of the type shown in the Taylor Patent 2,028,110. This motor includes three control terminals which are marked R, W, and B, and is adapted to assume intermediate positions depending upon the relative values of resistances connected between terminals R and W and between terminals R and B. When equal resistances are connected between terminals R and W and between terminals R and B, this motor will assume mid position as shown which causes closing of mercury switches 119 and 120 for operating the compressor motor 9 at intermediate speed. If the resistance between terminals R and W is decreased without corresponding decrease in resistance between terminals R and B, the motor 69 will operate in a counter-clockwise direction for decreasing the compressor speed, and conversely, if the resistance between terminals R and B is decreased without corresponding decrease in resistance between terminals R and W, the motor 69 will operate in the clockwise direction for increasing the compressor speed.

The pull-in coil 137 of the relay 70 is controlled by the mercury switch 91 of the step controller 67. When outside temperature is at or above 75° F., this mercury switch will be tilted as shown for bridging its left-hand electrodes and this will energize pull-in coil 137 as follows: transformer secondary 94, wires 96, 101 and 150, left-hand electrodes of switch 91, wire 151, pull-in coil 137, and wires 152, 105, 99 and 100 to transformer secondary 94. It will thus be apparent that when outside temperature is at or above 75° F., the coil 137 will be energized for causing the switch arms 138, 139 and 140 to engage their "in" contacts. However, when outside temperature is below 75° F., these switch arms will engage their "out" contacts.

Assuming that outside temperature is above 75° F., thereby energizing the relay 70, the switch arms 138, 139, and 140 will engage the "in" contacts, as shown. Engagement of switch arm 139 with contact 142 will connect terminal R of the motor 69 to the slider 128 of the summer thermostat 71 through wire 153, switch arm 139, contact 142, and wire 154. Engagement of switch arm 138 with contact 141 will connect terminal W of motor 69 to the right-hand end of resistance 129 through wires 155 and 156, while engagement of switch arm 140 with contact 143 will connect terminal B to the left-hand end of resistance 129 through wires 157 and 158. Consequently, the summer thermostat 71 is placed into control of the motor 69 which controls the compressor speed. With the space temperature at an intermediate value, the slider 128 engages the center of resistance 129 which divides the resistance 129 equally between terminals R and W and terminals R and B. This causes the motor 69 to assume the position shown at which mercury switches 119 and 120 are closed for operating the compressor at intermediate speed. Upon rise in space temperature, the slider 128 will shift to the left along resistance 129 thereby decreasing the portion of this resistance which is between terminals R and B, while increasing the portion between terminals R and W. This will cause the motor 69 to rotate proportionately in the clockwise direction thereby causing closing of the switch 121 for operating the compressor at high speed. Upon decrease in space temperature from this intermediate value, the slider 128 will

shift to the right along resistance 129 thereby decreasing the proportion of this resistance which is between terminals R and W, which will cause the motor 69 to operate in the counter-clockwise direction thus tilting mercury switch 120 to open position which will cause the compressor to operate at low speed. Upon continued decrease in space temperature, the motor 69 will rotate further in the counterclockwise direction thus causing opening of switch 123 to stop the compressor when the space temperature falls to 75° F. Therefore, when outside temperature is at or above 75° F., the summer thermostat 71 is placed in control of the compressor, acting to place the compressor into operation at low speed when space temperature rises above 75° F. and to gradually increase the compressor speed upon increase in space temperature for causing the compressor to operate at maximum speed when the space temperature rises to 80° F.

When outside temperature falls below 75° F., the mercury switch 91 of step controller 67 will be tilted so as to unbridge its left-hand electrodes and bridge its right-hand electrodes. This unbridging of the left-hand electrodes will break the energizing circuit or the relay 70 thereby causing the switch arms 138, 139 and 140 to engage their "out" contacts. This will completely disconnect the summer thermostat 71 from the motor 69. Engagement of the switch arm 139 with contact 145 will connect terminal R of motor 69 to the slider 133 of the discharge thermostat 73 by wires 153, 160 and 161. If the slider 133 is engaging the left-hand end of resistance 134 as occurs when the discharge temperature is sufficiently high, this circuit from terminal R of the motor will be carried through wire 162 to the slider 130 of the winter thermostat 72. Due to the switch arm 138 engaging contact 144, terminal W of motor 69 will be connected to the left-hand end of resistance 131 by wires 155 and 163. Also due to the switch arm 140 engaging contact 146, terminal B of motor 69 will now be connected by wires 157, 164, and 165 to the right-hand end of resistance 131. Therefore when the relay 70 is deenergized and the discharge temperature is at or above 65° F., the thermostat 72 will be in control of the step controller motor 69. If the space temperature is above 72° F., terminals R and W of the motor will be substantially short-circuited for thereby rotating the shaft 118 of the step controller in a direction for stopping the compressor. As the space temperature decreases below 72° F., the slider 130 will begin moving to the right across resistance 131 thereby inserting a portion of this resistance between terminals R and W and removing this resistance from between terminals R and B. This will cause the motor shaft 118 to rotate proportionately in a clockwise direction thus starting the compressor and increasing its speed as the space temperature falls. When the space temperature falls to 70° F., the motor 69 will assume the position for operating the compressor at maximum speed.

It will be noted that the right-hand end of the resistance 134 of discharge controller 73 is connected by wires 167, 166, 165, 164, contact 146, switch arm 140, and wire 157 to terminal B of motor 69. If the discharge temperature begins falling below 65° F., the slider 133 will begin moving to the right along resistance 134. This will insert resistances into the circuit between terminal R of motor 69 and the slider 130 of thermostat 72 thereby decreasing the effect of this thermostat upon the motor. Also as the slider 133

shifts to the right along resistance 134, it acts to decrease the portion of resistance 134 which is connected between terminals R and B of motor 69 for causing this motor to increase the compressor speed. Thus as the discharge temperature falls below the setting of the discharge thermostat 73, this thermostat acts to increase the compressor speed independently of the thermostat 72 for thereby preventing the discharge temperature from falling too low. It will be noted that resistance 168 is connected to the wires 161 and 165 and is thus connected across terminals R and B of motor 69. The purpose of this resistance is to balance out the effect of the resistance 134 of controller 73 which is connected between terminals R and W of motor 69 when this thermostat is in satisfied or normal position. This resistance 168 should be equal in value to the resistance 134.

From the description thus far, it will be seen that when the outside temperature is above 75° F., the summer thermostat 71 is placed in control of the compressor speed controller and acts in a manner to increase the compressor speed as space temperature increases. When outside temperature falls below 75° F., the step controller 67 deenergizes the relay 70 which disconnects the summer thermostat 71 from the compressor speed controller and places the winter space thermostat 72 and the discharge controller 73 in control of the compressor speed controller. At this time, the controller 72 acts to increase the compressor speed upon fall in space temperature and the discharge thermostat 73 acts to prevent the discharge temperature from falling below the desired value.

Referring now to the controls for tank 46, it will be noted that this tank is closed at its top to provide an air space above the water level. The water level with this tank is controlled for maintaining a substantially constant pressure within the tank, the pressure controller 75 being selectively connected to the valve 60 or the valve 44 through the relay 76. The pressure controller 75 may consist of a bellows 170 which is connected to the tank 46 by a tube 171. This bellows actuates a bell-crank lever having an actuating arm 172 and a slider 173 cooperating with a resistance 174. Upon increase in pressure within tank 46, the bellows 170 will expand against the action of spring 175 for causing the slider 173 to shift to the left across resistance 174. This instrument may be adjusted in a manner to cause the slider 173 to engage the left-hand end of resistance 174 when the tank pressure is at 40 pounds per square inch and to engage the right-hand end of resistance 173 when the pressure is at or below 30 pounds per square inch.

The relay 76 includes a pull-in coil 176 which actuates switch arms 177, 178, 179, 180, and 181. The switch arms 177, 178, 179, and 180 cooperate with "out" contacts 182, 183, 184, and 185 and switch arms 178, 179, 180, and 181 cooperate with "in" contacts 186, 187, 188, and 189. When the coil 176 is deenergized, the switch arms 177, 178, 179, and 180 engage their "out" contacts and when the coil 176 is energized, the switch arms 178, 179, 180, and 181 engage their respective "in" contacts. The coil 176 is controlled by the mercury switch 91 of the outdoor temperature step controller 67. When outdoor temperature falls below 75° F., the mercury switch 91 is tilted for bridging its right-hand electrodes. This will energize coil 176 as follows: transformer sec-

ondary 94, wires 96, 101 and 150, right-hand electrodes of switch 91, wire 190, coil 176, wires 191, 192, and 100 to secondary 94. Therefore when outdoor temperature is below 75° F., the coil 176 is energized for causing the various switch arms to engage their "in" contacts. When outdoor temperature is above 75° F., the coil 176 is de-energized for causing the switch arms to engage their "out" contacts, as shown.

The three-way valve 44 is positioned by means of a proportioning motor 195 having terminals R, W, and B. When the relay 76 is deenergized due to outside temperature being above 75° F., the slider 173 of the pressure controller 75 is connected to terminal R of motor 195 by wire 196, switch arm 179, contact 184, and wire 197. Also, the right-hand end of resistance 174 is connected to terminal B by wire 198, switch arm 180, contact 185, and wire 199. At this time, the left-hand end of resistance 173 is connected by wire 200, switch arm 178, contact 183, and wire 201 to terminal W of motor 195. Therefore when outside temperature is above 75° F., the pressure controller 75 is placed in control of the motor 195 which positions the three-way valve 44. With the slider 173 in the position shown, the resistance 174 will be divided equally between terminals R and W and terminals R and B of motor 195 thus causing this motor to assume an intermediate position which permits the water flowing through pipe 43 to be divided between the storage tank 46 and the waste pipe 58. If the pressure within tank 46 falls due to withdrawing of water from this tank for domestic use, the slider 173 will shift to the left across resistance 174 thus decreasing the portion of this resistance between terminals R and B for causing the motor 195 to position valve 44 in a manner to increase the flow of water into tank 46. Conversely, upon increase in pressure with the tank 46, the slider 173 will shift to the left across resistance 174 thereby causing the motor 195 to position valve 44 for decreasing the flow of water into tank 46. When the pressure within this tank rises to 40 pounds per square inch, the valve 44 will be positioned for preventing further flow of water into this tank.

When outside temperature falls below 75° F., the mercury switch 91 will energize the relay 176 for causing the various switch arms to disengage their "out" contacts and to engage their "in" contacts. This will completely disconnect the pressure controller 75 from the three-way valve motor 195. Due to the switch arm 181 of relay 76 engaging contact 189, terminals R and B of motor 195 will be short-circuited through wires 197, 202, switch arm 181, contact 189, and wire 199. This causes the motor 195 to position the valve 44 for causing all of the water flowing in pipe 43 to flow into tank 46.

Due to the relay 76 now being energized, the slider 173 of pressure controller 75 will be connected to terminal R of motor 61 which operates the valve 60 by wire 196, switch arm 179, contact 181, and wire 203. The right-hand end of resistance 174 will be connected to terminal B of motor 61 by wire 198, switch arm 180, contact 188, and wire 204, while the left-hand end of resistance 174 will be connected to terminal W of motor 61 by wire 200, switch arm 178, contact 186 and wire 205. Therefore the pressure controller 75 at this time is placed under the control of the valve 60 which controls the flow of city water through pipe 59 into the coil 13 of condenser 12, and thus through pipe 41, valve 42,

pipe 43, valve 44, and pipe 45 into tank 46. When the pressure in the tank is above 40 pounds per square inch, the controller 75 will cause the valve 60 to be closed, while upon fall in pressure below this value the valve 60 will be gradually opened.

When outside temperature is above 75° F., thus causing the relay 76 to be deenergized, the switch arm 177 engages the contact 182 which connects terminals R and W of motor 61 through wires 203, 206, switch arm 177, contact 182, and wire 205. From the foregoing, it will be seen that when outside temperature is above 75° F., the pressure controller 75 is placed in control of the three-way valve 44 and the valve 60 is driven to closed position. However, when outside temperature falls below this value, the pressure controller 75 is placed in control of the valve 60 and the three-way valve 44 is driven to a position for causing all of the water flowing through pipe 43 to flow into the tank 46.

The throttling valve 42 is provided for the purpose of restricting the flow of water through the coil 13 in condenser 12 for thereby insuring that the water is heated to the desired point during its flow through this coil. This valve is positioned by a proportioning motor 208 which is controlled by the thermostat 77 responsive to the temperature of the water in tank 46. The thermostat 77 may comprise a bellows 209 which actuates a lever arm 210 against the action of spring 211. The lever arm 210 actuates a slider 212 which cooperates with a resistance 213 to form a control potentiometer for the motor 208. This lever 210 also actuates a corrector arm 214 which cooperates with a center tapped resistance 215. The bellows 209 is connected by a capillary tube 216 to a bulb 217 located in the tank 46 (Figure 1).

The right-hand end of the resistance 213 is connected by wires 218 and 218a to terminal B of motor 208 and the lefthand end of this resistance is connected by wires 219 and 220 to terminal W of this motor. The slider 212 and corrector arm 214 of thermostat 77 are electrically connected and the resistance 215 is connected by wires 221 and 222 to terminal R of motor 208. Thus the slider 212 is connected to terminal R through the corrector arm 214 and corrector resistance 215. The thermostat 77 is of the wide range type and causes motor 208 to shift valve 42 from wide open position to a minimum flow position upon movement of the slider 212 over but a small portion of the resistance 213. This controller may be arranged so that the slider 212 engages the right-hand end of resistance 213 when the water temperature rises to 160° F. while engaging the left-hand end of this resistance when the water temperature falls to 120° F. Upon a slight movement of the slider 212 to the right across resistance 213, the resistance between terminals R and B will be decreased for causing valve 42 to open thereby increasing the flow of water through coil 13 for allowing the water temperature to fall. Conversely, upon a slight decrease in temperature, the slider 212 will be shifted slightly to the left across resistance 213 thus decreasing the resistance between terminals R and W of motor 208 for positioning the valve 42 in a manner to restrict the flow of water. This causes the water to be more highly heated as it flows through the coil 13. The linkage between valve 42 and motor 208 must be adjusted so that the motor cannot close the valve completely even when the motor reaches the end

of its travel. This prevents the flow of water through the condenser from being completely stopped by valve 42.

It is a feature of this invention to prevent operation of the compressor during peak load periods for the power service and to provide for increasing the temperature in tank 46 at a predetermined time before the peak load period in order to provide an adequate supply of hot water to last through the period when the compressor is stopped. This result is obtained by the timer 78 and a pair of compensating or adjusting potentiometers 225 and 226. The timer 78 may consist of a suitable synchronous motor and gear train mechanism 227 having a shaft 228 which is rotated one revolution every twenty-four hours. This shaft 228 carries cams 229 and 230 which actuate mercury switches 231 and 232. For purposes of illustration, it is assumed that only one peak load period occurs each day, and the cams 229 and 230 are provided with single raised portions corresponding to the peak load period. It will be noted that upon clockwise rotation of the shaft 228, the raised portion of the cam 229 will engage its cam follower a predetermined time in advance of the time when the raised portion of the cam 230 engages its cam follower.

The mercury switch 232 controls the compressor relay 74, the energizing circuit for the relay 74 also being controlled by the mercury switches 92 and 93 of the outdoor step controller 67. When outdoor temperature is above 75° F., the compressor relay 74 will be energized through mercury switches 93 and 232 as follows: transformer secondary 94, wire 96, wire 97, mercury switch 93, wire 233, wire 234, mercury switch 232, wire 235, relay coil 111, and wires 99 and 100 to secondary 94. When outside temperature falls below 75° F., the mercury switch 93 will be opened which will break the circuit just traced for preventing operation of the compressor. When outside temperature falls to 60° F. for causing closing of mercury switch 93, the energizing circuit for relay 74 will be established through this mercury switch as follows: secondary 94, wires 96, 101 and 102, mercury switch 92, wire 236, wire 234, mercury switch 232, wire 235, relay coil 111, and wires 99 and 100 to secondary 94. It will therefore be seen that the mercury switch 232 of the timer 78 is always in circuit with the compressor relay 74 and that when this mercury switch is open, the relay 74 is deenergized for preventing operation of the compressor.

The mercury switch 231 has its common electrodes connected by wires 237 and 222 to terminal R of motor 208. The right-hand electrode of this switch is connected by wire 238 to the slider 239 of potentiometer 226, and the left-hand electrode of this switch is connected by wire 240 to the slider 241 of potentiometer 225. The resistances 242 and 243 of these potentiometers are connected across terminals W and B of motor 208, as shown. It will therefore be seen that the mercury switch 231 acts to place either the potentiometer 225 or the potentiometer 226 across the motor control terminals in parallel with the thermostat 77. Each of these potentiometers acts to determine the temperature of the water which will be maintained by the thermostat 77. For instance, if the slider 239 of potentiometer 226 is shifted to the right across its resistance 243, it will decrease the amount of resistance between terminals R and B and increase the amount of resistance between terminals R and W. This

will cause the valve 42 to be opened further thereby lowering the temperature of the water flowing from coil 13. Similarly, if the slider 241 of potentiometer 225 is moved to the right across its resistance 242, it will decrease the portion of this resistance between terminals R and W for thus causing valve 42 to be further closed thereby raising the temperature of the water leaving coil 13. With the sliders 239 and 241 in the positions shown, the potentiometer 226 will cause a relatively low water temperature to be maintained while the potentiometer 225 will cause a relatively high water temperature to be maintained.

During normal operation of the system, the mercury switch 231 of timer 78 will place the potentiometer 226 into the control circuit of motor 208 for thereby causing the tank thermostat 77 to maintain a relatively low water temperature such as 125° F. As the peak load period for the power service approaches, the cam 229 will tilt mercury switch 231 to its opposite position for removing potentiometer 226 from the motor control circuit and substituting the potentiometer 225. This will raise the water temperature maintained by the tank thermostat 77. Thereafter, the cam 230 will cause opening of mercury switch 232 for stopping the compressor during the peak load period. It will be apparent from the foregoing that during normal operation of the system, the tank thermostat 77 operates to maintain a relatively low tank temperature for thus permitting the refrigeration system to operate at a low head pressure securing maximum operating efficiency. Then as the peak load period for the power service approaches, the timer 78 substitutes the potentiometer 225 into the control circuit in place of potentiometer 226 for thereby raising the tank temperature so as to store sufficient heat for carrying the system over the peak load period when the compressor is stopped.

Referring to the pump controller 51, this controller may consist of a pull-in coil 250 for operating a switch arm 251 engaging a contact 252. The pull-in coil 250 is connected to the mercury switches 92 and 93 by means of wire 253 and wires 233 and 236. The left-hand end of coil 250 is also connected to the transformer secondary 94 by wires 100, 102 and 254. It will therefore be apparent that whenever the mercury switch 92 or 93 are positioned for permitting operation of the compressor, the pump starter 51 will be energized for placing the pump 50 into operation.

Operation

With the parts in the position shown, the outdoor temperature is above 75° F. as indicated by the slider 85 of the step controller 65 engaging the right-hand end of resistance 86. This has caused the step controller motor 66 to assume its clockwise limit of rotation at which the mercury switch 91 is positioned for bridging its left-hand electrodes, the mercury switch 92 is open, and the mercury switch 93 is closed. Due to the mercury switch 92 being open, the W valves 31, 35, and 51 are closed while due to switch 93 being closed the S valves 32, 36, and 56 are open. This closure of mercury switch 93 also has caused energization of the pump motor starter 51 for placing the pump in operation and also has energized the compressor relay 74 through switch 232 of the timer 78 for placing the compressor under the control of the step controller 68.

Due to the S valves being open and the W valves being closed, cold water will be withdrawn

from the coil 18 of evaporator 17 through pipe 34 passing through valve 36 and pipe 48 to the inlet of pump 49 from which it passes through pipe 52 to the coil 7 which acts as a cooling coil. The water leaving coil 7 then flows through pipes 53 and 54 through the valve 56 and pipe 33 back to the coil 18. The coil 7 in the conditioning chamber 1 is therefore connected into circuit with the evaporator coil 18 at this time for thereby cooling the air passing to the space. At the same time, the pump 25 withdraws water from the well 28 and passes it through the coil 6 which acts to precool the incoming air. The water leaving coil 6 then flows through pipe 30, valve 32, and pipe 49 to the condenser coil 13 for thereby cooling the refrigerant compressed by the compressor. The water in passing through the condenser becomes heated and flows through valve 42 to the valve 44 which divides this stream between the storage tank 46 and the waste pipe 58. At this time, it will be noted that the relay 76 is deenergized which acts to place the pressure controller 75 in control of the motor 195 which positions the three-way valve 44. Thus when the pressure within tank 46 is at the predetermined value, such as 40 pounds per square inch, the valve 44 assumes the position shown which causes all of the water leaving condenser coil 13 to pass through the waste pipe 58 to the sump 38 from which it flows through the subterranean ditch 39 back to the well 28. As the pressure within tank 46 lowers, the motor 195 will position valve 44 for permitting flow of a portion of the water into tank 46.

With the mercury switch 91 in the position shown, the relay 70 is energized which acts to place the compressor step controller under the control of the summer thermostat 71. This thermostat acts to increase the compressor speed as the space temperature increases to thereby vary the refrigeration in accordance with the cooling load upon the system.

The thermostat 71 which is responsive to the temperature of the water in tank 46 will control the valve 42 in a manner to close valve 42 progressively with decrease in temperature within tank 46. This restriction of the water flow causes the water to be heated to a higher temperature as it flows through the condenser 12 and thus provides for maintaining the water in tank 46 at the desired temperature. With the timer in the position shown, the low temperature potentiometer 226 is connected into the control circuit of motor 208 which causes the thermostat 71 to maintain the tank temperature at the desired normal value. As the peak load period for the power service approaches, the cam 229 will tilt mercury switch 231 to its opposite position for placing the high temperature potentiometer 225 into the motor control circuit thereby causing the tank water temperature to be increased for thereby storing up additional heat. When the peak load period occurs, the mercury switch 232 of the timer 78 will be opened which acts to deenergize the compressor relay 74 thereby placing the compressor out of operation.

When outside temperature falls below 75° F., the mercury switch 91 of the step controller 67 will tilt to its opposite position which acts to energize the relay 76 and to deenergize the relay 70. Energization of the relay 76 will disconnect the pressure controller 75 from the three-way valve motor 195 and connect this pressure controller to the city water supply valve motor 61. Energization of this relay will also cause motor 75

195 to position the valve 44 for passing all of the water flowing through pipe 43 into the tank 46. Deenergization of the relay 70 will cause the summer thermostat to be disconnected from the step controller motor 69 and to place this motor under the control of the winter space thermostat 72 and the discharge thermostat 73. However, due to the opening of switch 93 of step controller 67 at this time, the relays 51 and 74 will be deenergized and the compressor 8 and the circulating pump 49 will not be in operation. With outside temperature at this value, no conditioning is necessary for the space and until outside temperature falls to approximately 60° F., no heating will be necessary.

When outside temperature falls to 60° F., the mercury switch 92 will close which will energize the pump starter 51 for placing the pump 49 into operation and will also energize the compressor relay 74 for permitting operation of the compressor under the control of the winter space thermostat 72 and the discharge thermostat 73. These thermostats will then operate to control the speed of the compressor in a manner to prevent the space temperature from falling below the setting of thermostat 72 and to prevent the discharge temperature from falling below the setting of discharge thermostat 73.

At this time, the S valves 32, 36, and 56 will be deenergized and the W valves 31, 35, and 57 will be energized through the mercury switch 92. Due to valves 31, 35, and 57 being opened, water will flow from the coil 7 through pipes 53 and 55 to valve 51, then through pipe 40 to coil 13 of condenser 12 wherein it is heated. This now heated water will then flow through the throttling valve 42 to the three-way valve 44 which will now be positioned for passing all of this water to tank 46. Water will then flow from this tank through the circulating pipe 47 and pipe 48 to the pump 49 which discharges this hot water through the pipe 52 to the coil 7. Also, the pump 25 will withdraw water from well 28 passing it through the coil 6 which acts as a pre-heater, this water then passing through pipe 30, valve 31, and pipe 33 to coil 18 in the evaporator 17 and through pipe 34, valve 35, and pipe 37 to the sump 38. Therefore when the system is operating on the heating cycle, the coil 7 receives hot water from the storage tank 46 which in turn is heated by the condenser 12. Also, the well water after preheating the air passes through the evaporator 17 for thus providing a source of heat for the refrigeration system.

During the heating cycle, the thermostat 71 will control the throttling valve 42 just as it does during the cooling cycle. Also, the timer 78 will act to stop the compressor during peak load periods and to raise the water temperature in tank 46 prior to these peak load periods for thereby storing up heat for use during the peak load periods. It should be noted that the timer 78 stops only the compressor and permits the circulating pump 50 to continue to operate for thereby supplying heat to the space even when the compressor is not operating.

From the foregoing description, it will be apparent that this invention has provided a system for heating and cooling a space by means of a refrigeration system, the system being caused to selectively heat or cool by changing the water piping connections, thereby permitting the refrigeration system to operate in the same manner at all times. It will also be apparent that this invention provides an automatically con-

trolled system for maintaining proper space conditions both in summer and in winter and for also maintaining a supply of domestic hot water.

While throughout this description definite values of temperature and pressure have been mentioned for illustrative purposes, it will be apparent that these values may be varied as desired for different installations and applications of this invention. Also, while I have shown but one embodiment of this invention, the invention is not limited to the specific arrangement illustrated. As many modifications of the system which are within the scope of the invention will be apparent to those skilled in the art, I desire to be limited only by the scope of the appended claims.

I claim as my invention:

1. In a reversible cycle system for heating or cooling a space, in combination, a refrigeration system having an evaporator, a condenser and a compressor, a heat exchanger in heat exchange relationship with said space, fluid conveying means including valve means for selectively connecting said heat exchanger into fluid circulating relationship with said evaporator or said condenser, thermostatic means for controlling said compressor, changeover means for controlling said valve means and also controlling said thermostatic means in a manner to cause said thermostatic means to start said compressor upon fall in temperature when said heat exchanger is connected to said condenser and to start said compressor upon rise in temperature when said heat exchanger is connected to said evaporator, and outside temperature responsive means for controlling said changeover means and for preventing operation of said compressor when outside temperature is between predetermined values.

2. In a reversible cycle system for heating and cooling a space, in combination, a refrigeration system having an evaporator device, a condenser device and a compressor, a heat exchanger in heat exchange relationship with said space, a storage tank, fluid conveying means including valve means for selectively connecting said heat exchanger into fluid circulating relationship with said evaporator device or said condenser device while maintaining said storage tank connected for receiving fluid from one of said devices, thermostatic means for controlling said compressor, changeover means for controlling said valve means and also controlling said thermostatic means in a manner to cause said thermostatic means to start said compressor upon fall in temperature when said heat exchanger is connected to said condenser device and to start said compressor upon rise in temperature when said heat exchanger is connected to said evaporator device, and means for controlling the temperature in said storage tank.

3. In a reversible cycle system for heating and cooling, in combination, a refrigeration system having an evaporator device and a condenser device, a heat exchanger in heat exchange relationship with a medium to be conditioned, a storage tank for fluid, means for selectively connecting said heat exchanger into fluid circulating relationship with either said evaporator device or condenser device while maintaining said storage tank connected for receiving fluid from one of said devices, a flow controller for controlling the flow of fluid through said one device, and means responsive to the temperature of the fluid for controlling said flow controller.

4. In a reversible cycle system for heating and cooling, in combination, a refrigeration system having an evaporator device and a condenser device, a heat exchanger in heat exchange relationship with a medium to be conditioned, a storage tank for fluid, means for selectively connecting said heat exchanger into fluid circulating relationship with either said evaporator device or condenser device while maintaining said storage tank connected for receiving fluid from one of said devices, flow control means for controlling the flow of fluid into said storage tank, and means responsive to the temperature of the fluid in said storage tank for controlling said flow control means.

5. In a reversible cycle system for heating and cooling, in combination, a refrigeration system having an evaporator device and a condenser device, a heat exchanger in heat exchange relationship with a medium to be conditioned, a storage tank for fluid, means for selectively connecting said heat exchanger into fluid circulating relationship with either said evaporator device or condenser device while maintaining said storage tank connected for receiving fluid from one of said devices, a flow controller for controlling the flow of fluid through said one device, means responsive to the temperature of the fluid for controlling said flow controller, flow control means for controlling the flow of fluid into said storage tank, and means responsive to the quantity of fluid in said storage tank for controlling said flow control means.

6. In a reversible cycle system for heating and cooling, in combination, a refrigeration system having an evaporator device and a condenser device, a heat exchanger in heat exchange relationship with a medium to be conditioned, a storage tank for fluid, means for selectively connecting said heat exchanger into fluid circulating relationship with either said evaporator device or said condenser device while maintaining said storage tank connected for receiving fluid from one of said devices, temperature responsive means for controlling said refrigeration system, temperature responsive means for controlling the temperature in said storage tank, and timing means for varying the temperature maintained in said storage tank and thereafter preventing operation of said refrigeration system.

7. In a reversible cycle system for heating and cooling, in combination, a refrigeration system, means adapted to either heat or cool a space and including a storage tank for conditioning medium which is changed in temperature by the refrigeration system, thermostatic means responsive to the temperature of the stored medium for controlling the temperature of said medium, timing means for limiting operation of said refrigeration system for predetermined periods, and means actuated by said timing means for varying the temperature of the stored medium prior to said periods.

8. In a reversible cycle system for heating and cooling, in combination, a refrigeration system, means adapted to either heat or cool a space and including a storage tank for conditioning medium which is changed in temperature by the refrigeration system, a circulating pump for circulating the conditioning medium, temperature responsive means for controlling the circulating pump, thermostatic means for controlling the temperature of the stored medium, timing means for limiting the operation of said refrigeration system during predetermined periods while per-

mitting said circulating pump to operate, and means actuated by the timing means for varying the temperature of the stored medium prior to said periods.

9. In a system of the class described, in combination, a refrigeration system, means for conditioning a space, said refrigeration system including a compressor, a storage tank for storing conditioning medium which is changed in temperature by said refrigeration system, a circulating pump for circulating conditioning medium between said tank and said conditioning means, temperature responsive means for controlling said compressor and circulating pump, and timing means for limiting the operation of said compressor during predetermined periods while permitting said circulating pump to continue to operate under the control of said temperature responsive means.

10. In a system for conditioning the air in a space, in combination, a refrigeration system for changing the heat content of the air in said space, a storage tank for medium which is changed in temperature changing capacity by said refrigeration system, thermostatic means for controlling the temperature changing capacity of the medium in said storage tank, timing means for placing the refrigeration system out of operation during predetermined periods, and means controlled by said timing means for adjusting said thermostatic means prior to said periods in such manner that the temperature changing capacity of said medium is increased.

11. In a system for conditioning a space, in combination, a heat exchanger in heat exchange relationship with said space, a storage tank for heat exchange medium, piping means for circulating heat exchange medium from said storage tank through said heat exchanger, thermostatic means for controlling the circulation of heat exchange medium, a power consuming means for changing the temperature of the medium in said storage tank, thermostatic means responsive to the temperature of said medium for controlling said power consuming means for maintaining said medium at a predetermined temperature so that it has a predetermined heat exchange capacity, timing means for placing said power consuming means out of operation during predetermined periods, and means controlled by said timing means for adjusting said thermostatic means prior to said periods in such a manner as to increase the heat exchange capacity above said predetermined capacity.

12. In a reversible refrigeration system for heating or cooling a space, in combination, a conditioning chamber through which air is passed to said space, a heat exchanger in said chamber, a refrigeration system having an evaporator and a condenser, piping means between said heat exchanger, evaporator, and condenser, circulation controlling means, two-position type control means for said circulation controlling means, said control means having a first position causing heat transfer fluid to circulate from said

condenser to said heat exchanger and a second position causing heat transfer fluid to circulate from said evaporator to said heat exchanger, thermostatic means for controlling the power input to said refrigeration system, a low limit thermostat responsive to the temperature of the air discharged from said heat exchanger for controlling the power input in a manner to prevent the discharge air temperature from falling below a predetermined value, and changeover means for actuating said control means to reverse the system from heating to cooling, said changeover also controlling the action of said thermostatic means and of said low limit thermostat to cause said thermostatic means to operate on temperature rise and to render said low limit thermostat ineffective to prevent the temperature of the discharge of air from falling below said predetermined value when the control means is operated to place the system on cooling.

13. An apparatus for serially utilizing a single supply of water for both heat exchange and a second water using system, said apparatus comprising a heat exchanger, a line connected to said single supply of water for continuously supplying water therefrom to the heat exchanger, a second line from the outlet of said heat exchanger connecting with a second water using system, a modulating valve in one of said lines for controlling the flow of water through the heat exchanger, thermostatic means for automatically controlling said modulating valve in accordance with the temperature condition of the water in said apparatus, and valve means operated in response to pressure in the apparatus to relieve the apparatus of water flowing through the heat exchanger from said single water supply in excess of the requirements of said second water using system while maintaining said second water using system under adequate pressure.

14. An apparatus for serially utilizing a single supply of water for both heat exchange and domestic use, said apparatus comprising a heat exchanger, a line connected to said single supply of water for continuously supplying water therefrom to the heat exchanger, a second line from the outlet of said heat exchanger connecting with a domestic water supply, a modulating valve in one of said lines for controlling the flow of water through the heat exchanger, thermostatic means for automatically controlling said modulating valve in accordance with the temperature of the water in said apparatus, and valve means operated in response to pressure in the apparatus which permits continued flow of water from said single source of supply through said heat exchanger and diverts that portion of the water flowing through the heat exchanger from the single water supply which is not needed in said domestic water supply while maintaining said domestic water supply under adequate pressure.
